United States Patent

Des. 235,723
Patented July 8, 1975

235,723

SERVING TRAY OR SIMILAR ARTICLE

Kurt M. Vorcheimer, 92 Pinehurst Ave.,
New York, N.Y. 10033

Filed July 30, 1973, Ser. No. 383,886

Term of patent 3½ years

Int. Cl. D7—99

U.S. Cl. D7—70

FIG.1

FIG.2

FIG.3

FIG.4

FIG. 1 is a top plan view of a serving tray or similar article showing my new design;

FIG. 2 is a bottom plan view thereof;

FIG. 3 is a side elevational view thereof; and

FIG. 4 is an end elevational view thereof.

The top of the serving tray or similar article is planar, except for the circular recesses, and the curvilinear and rectilinear ornamentation adjacent thereto.

I claim:

The ornamental design for a serving tray or similar article, substantially as shown and described.
